[57] CLAIM

The ornamental design for a set of icons for a computer screen, as shown and described.

DESCRIPTION

FIG. 1 is a perspective view of a set of icons for a computer screen; and,

FIG. 2 is a front view thereof, on an enlarged scale.

The broken line drawing of a computer screen in FIGS. 1 and 2 is for illustrative purposes only and forms no part of the claimed design.

1 Claim, 2 Drawing Sheets

FIG. 1

FIG. 2
